UNITED STATES PATENT OFFICE.

WILLIAM E. ARNOLD, OF ROCHESTER, NEW YORK.

SASH-FASTENER.

Specification of Letters Patent No. 12,500, dated March 13, 1855.

To all whom it may concern:

Be it known that I, WILLIAM E. ARNOLD, of the city of Rochester, in the county of Monroe and State of New York, have invented a new and Improved Sash-Lock, of which the following is a full and exact description, reference being had to the accompanying drawings and to the letters of reference marked thereon, same letters signifying like parts in all the drawings.

And of said drawings Figure 1 is a perspective view of the lock as applied to a section of sash-stile. For the sake of clearness the lock is shown in the drawing as applied to the outside of the stile, but it is evident that in most cases its appearance and convenience would be promoted by sinking it in flush with the face of the stile. Figs. 2, 3, 4 and 5 are details of the various parts. Figs. 6 and 7 exemplify the action of the curved groove and curved wedge on the bolt and curved shank. Fig. 8 is a diagram, exhibiting a plan of the whole lock when together. In this figure the outer case is drawn in black lines; the outline of the bolt in blue; the primary slide in red; and the secondary slide or tumbler (shown separate and detached in Fig. 4) is drawn in green lines, with its projecting angle resting in the notch *h*. Fig. 9 is an explanatory diagram.

The nature of my invention consists in arranging a bolt and movable slide within a case so as to impart a nearly horizontal motion to said bolt and thus form a neat and efficient sash lock; and also in providing suitable means to prevent any pressure on the bolt in the direction of the arrow (Fig. 1) from withdrawing it from its place.

To enable others skilled in the art to make and use my invention I will proceed to describe its principles and mode of action by means of the above-described drawings.

I construct a bolt (B) of the form shown in the drawings and having a curved shank as therein depicted. I also construct a sliding piece calculated to move vertically in the shell, box, or case of the lock, and having a curved groove or channel formed thereon by means of the projections (b) and (c). It will then be evident that, as the bolt is prevented by the edge of the box or casing from moving vertically, whenever the slide (S) descends from the position shown in Fig. 7 to that exhibited in Fig. 6,

the wedge-like projection (b) will act on the shoulder (B'') and eject the bolt. Now if the shank were straight and merely inclined at an angle with the bolt, although it would move perfectly horizontal it would be necessary either to have a very obtuse angle, or a very great amount of motion on the part of the slide to produce the desired amount of projection of the bolt. But the curved shank, operated on by the curved wedge, imparts not only a horizontal, but an angular or circular motion to the bolt whereby a compound movement partaking somewhat of the nature of a cycloid is secured. This motion will be very easily understood from the diagram Fig. 9. In this diagram we may at first suppose the bolt to revolve around the pivot (a) when acted upon by the circular wedge (w). In this case any point (p) in the bolt would describe a simple arc of a circle. But as the bolt is straight instead of curved and the bolt constrained in its motion by the edge of the case, the whole bolt and shank must move vertically through a distance equal to the difference between the radii *a c* and *a p*. The ultimate movement of the bolt then is compounded of the angular and vertical movements—these two (one being in the direction of a straight line and the other of a circle) tending to produce a horizontal cycloidal motion, in which the deviation of the angular, or circular, movement from a purely rectilineal and horizontal one, is rectified by the said vertical movement of the center (a)—that is of the whole bolt and shank. By these means I secure not only the nearly horizontal movement of the bolt but also the full amount of throw attainable by giving it a circular motion, and we are thus enabled to attain a sufficient projection of the bolt without the necessity for a wide lock case or a great vertical movement of the slide. All the parts of the lock also are easily fitted and moved, so that the ease of manipulation is increased and tear and wear both of the locks and sashes diminished. It is further evident that these motions of the bolt and slide might be produced from the outside of the case, by the simple action of a pin projecting through the slot (m), but in this case any action on the bolt would be equally productive of motion in the slide, and the lock would be comparatively insecure. To obviate this I connect

with the first sliding piece a secondary slide or tumbler (T), which is constructed as shown in detail in Fig. 4. A pin (P) on this slide passes through the slot (m) while a notch (n) which slips on to the projection (e) on the slide (s) enables it to have a slight angular motion of which (e) is the center. (x) is a projection against which the upper edge of the secondary slide or tumbler (T) will bear when a vertical pressure is exerted against the pin (P), and which will enable this pressure to move the slide (S), and consequently the bolt (B).

The notch (n) and pin (p) mutually act 15 as pivots to each other, and any force applied to the one will of course tend to rotate the slide about the other. Hence a force applied to the bolt (B) will act on the tumbler (T) through the slide (S), and projection (e) and will consequently tend to bring the projecting angle (g) of the tumbler (T) into one of the notches (h) in the case, when all further movement will be effectually prevented. But a vertical pressure on the pin 25 (p) will produce a rotary movement in a contrary direction, tending to release the tumbler from the notch (h) and allow it to act freely on the slide (S) through the projection (x). The same result, but in a less 30 perfect manner, may be obtained without the secondary slide or tumbler (T) by forming a projecting corner on the primary sliding block and recessing the outer case to suit. This modification of the primary sliding block is shown in Fig. 5, and the corresponding modification required in the case 35 will readily suggest itself to any intelligent mechanic. This method however, though cheaper, is not so perfect in its action, and I

would not propose to use it except in the 40 cheaper kind of cast iron locks.

The action of the secondary slide or tumbler is more clearly exhibited in Fig. 8—the different parts being there shown in variously colored lines as previously explained. The projecting angle of the tumbler (T) is there shown resting in the notch (h) which it will do from the force of gravity as well as from pressure on the bolt (B). 45

In order to avoid tearing and injuring the casing I allow the secondary slide or tumbler to move quite freely and unobstructedly during the latter part of the movement of the bolt, so as to make up for any slight 50 variations which may occur in the sash-frame or casing. But by means of the notches (h, h, h) and the action of the tumbler thereon during the first part of the bolt's motion the action of the stops in the 55 sash against the end of the bolt, when these stops become worn, or when there is a great amount of play between the sash and the window-casing, is effectually obviated. These notches also increase its security when 60 used as a railroad car lock—preventing the withdrawal of the bolt by any sudden jolt or jar.

What I claim as my invention and desire to secure by Letters Patent is— 65 The arrangement of the bolt B, traversing in guides; the slide S, and the tumbler T in relation to the case and the notches h thereon, as herein set forth.

WM. E. ARNOLD.
